UNITED STATES PATENT OFFICE.

FREDERIC S. JULIUS, OF PHILADELPHIA, PENNSYLVANIA.

BOTTLE PROTECTOR AND CLOSURE.

Application filed June 14, 1927. Serial No. 198,733.

According to present practice, milk, cream and allied dairy products are packaged almost entirely in bottles of standard form, which form consists of a wide mouth bottle containing an annular internal shoulder, the wall rising therefrom in such a manner that the diameter across the shoulder is slightly greater than that of the mouth. A sealing disc of paper or cardboard, of such size as to snugly fit the shoulder is used to seal the container and prevent loss of the contents or to prevent contamination of the material contained.

This prevailing practice is open to numerous objections, chief among which may be mentioned the following. That portion of the mouth over which the milk or other material must be poured is not protected at all by the present methods of sealing, and through handling or in other ways, this mouth portion becomes soiled or contaminated and thus may readily be the cause of disease transmission. The top of the container being recessed to receive the disc, makes it also easy for dirt or other foreign material to collect on the disc, and it is difficult, if not impossible, to prevent this contaminating material from gaining access to the contents of the bottle when the disc is removed. Furthermore, the present sealing disc is frequently removed with difficulty, and oftentimes the milk or other material is splashed upon one's clothes and other surrounding objects.

One of the main objects of this invention is to provide a novel protective device and closure member for use with milk bottles and like containers similar to those described, which is simple and easily applied and which by its construction and natural resilience snugly fits the mouth of the bottle, thereby effectively preventing contamination of the upper portion of the mouth after the container has been filled and my new closure applied.

My new closure has the added advantage that it is easily removable without splashing of the container contents, although while in place it is as effective in sealing the container as the closures known in the prior art, and it has the further property that it serves to protect the mouth of the container from chipping or breakage during handling or transportation.

These objects are attained by the use of my new protective device in connection with an ordinary disc closure, which is illustrated in

the accompanying drawings, of which Fig. 1 represents in section an ordinary milk bottle with my new combined closure and protective device in place; Fig. 2 is a plan view of the same; and Fig. 3 represents a perspective view of the protective member before being applied to a bottle.

In the drawings 1 represents the upper portion of an ordinary milk or cream bottle, having a wide mouth formed by the heavy bead 8, and containing on the inside an annular continuous shoulder 2. 10 represents my new protective device, which is made from paper or cardboard or other suitable material, one of the chief requirements being that this material shall be resilient. As shown in Fig. 3, this member is circular in form, but is not continuous. It is shaped to the form shown in section in Fig. 1, wherein 3 is a base portion which rests snugly on the annular shoulder, 4 being a continuation of the base 3, forming an upturned skirt or wall conforming to the inside of the mouth of the bottle, and continuous with the lip 5, which snugly overlaps the bead 8, as shown in the drawings. Thus it is seen that this protective member closely conforms to the inside of the mouth and to that portion thereof over which the contents must be poured.

According to the preferred practice of my invention, the protective member 10 is made of such size that when the free ends 11 just meet the diameter across the walls 4 is slightly greater than that of the mouth portion into which it must fit. As will be pointed out more in detail hereinafter, the combined effect of the natural resilience of the material and this size feature, creates a result which constitutes an essential characteristic of my new protective device.

In the practice of my invention, the protective device, initially in somewhat the condition shown in Fig. 3, is first set in the bottle. In order to accomplish this, it is necessary to overlap the ends 11, as shown at 9. This can be done only by restricting the natural diameter of this member, and in consequence of the fact that the material of which it is composed is resilient, stresses are set up within it which tend to expand this protective member.

After the member 10 has been set in place by forcing into position and overlapping the ends 11, an ordinary sealing disc 6, is forced into place in the usual manner so as to seat itself upon the base 3 of the protective mem-

ber, on the interior shoulder, thereby sealing the container in the usual manner.

It will be apparent that a double effect is secured through making the protective member of resilient material and of somewhat greater diameter than the aperture which it is to fit. The first effect thus produced is to cause the member to expand again after being compressed to fit it into the bottle, thereby 10 making it fit snugly into and over the mouth. The stresses due to the resilience also cause the protective member to hold itself firmly in the bottle, even when no closure disc has been put in place, and this feature is in itself of 15 considerable importance.

In order to remove the closure, it is only necessary to seize the exteriorly overlapping end 11 and pull it upward, thus removing both the member 10 and the disc 6 at once. It will 20 be apparent at once that the overlapping skirt portion 5 effectively prevents contamination of the upper pouring portion of the mouth, and also that any foreign material which may have collected in the recessed portion will 25 be unable to fall into the container, since the protective member and disc are pulled out together.

According to the provisions of the patent statutes, I have explained the principle and 30 operation of my invention and have illustrated and described what I now consider to represent its best embodiment. However, I desire to have it understood that, within the scope of the appended claims, the invention 35 may be practiced by other forms of construc-

tion than that particularly illustrated and described.

I claim:

1. The combination with a milk or like bottle having a neck provided interiorly with an annular shoulder, of a discontinuous annular mouth protector integrally formed of resilient material having a base resting upon said shoulder, a skirt rising from said base, and a lip extending outwardly from the upper edge of said skirt and overlying the top of the bottle, the free ends of said protector overlapping each other, and the resiliency of the protector urging its overlapping ends yielding outwardly to hold the protector in snug 45 engagement with the bottle.

2. The combination with a milk or like bottle having a neck provided interiorly with an annular shoulder, of a discontinuous annular mouth protector integrally formed of resilient material having a base resting upon said shoulder, a skirt rising from said base, a lip extending outwardly from the upper edge of said skirt and overlying the top of the bottle, the free ends of said protector overlapping each other, and the resiliency of the protector urging its overlapping ends yielding outwardly to hold the protector in snug 55 engagement with the bottle, and a sealing disc shaped to fit the mouth of the bottle closely resting upon the base portion of said mouth protector.

In testimony whereof, I sign my name.

FREDERIC S. JULIUS.
